UNITED STATES PATENT OFFICE.

CHAUNCEY A. HUGHES, OF ROSSVILLE, ILLINOIS.

DESIGN FOR A GAME-BOARD.

46,853.

Specification for Design.

Patented Jan. 12, 1915.

Application filed October 21, 1914. Serial No. 867,908. Term of patent 7 years.

To all whom it may concern:

Be it known that I, CHAUNCEY A. HUGHES, a citizen of the United States, residing at Rossville, in the county of Vermilion and State of Illinois, have invented a new, original, and ornamental Design for a Game-Board, of which the following is a specification, reference being had to the accompanying drawing, forming part thereof.

The figure is a face view of a game board showing my new design.

I claim:

The ornamental design for a game board, as shown.

CHAUNCEY A. HUGHES.

Witnesses:

G. A. RAY,

J. E. SWIFT.
